UNITED STATES PATENT OFFICE.

FOREST HALM, OF SHERMAN, CALIFORNIA.

CAR-FENDER.

No. 879,044.

Specification of Letters Patent.

Patented Feb. 11, 1908.

Application filed April 30, 1907. Serial No. 371,191.

To all whom it may concern:

Be it known that I, FOREST HALM, a citizen of the United States, residing at Sherman, in the county of Los Angeles and State of California, have invented a new and useful Car-Fender, of which the following is a specification.

This invention relates to car fenders, and the main object of the invention is to provide a fender which can readily be swung back under the car when not in use.

Other objects and advantages relate to details in the construction and arrangement as hereinafter set forth.

15 The accompanying drawings illustrate the invention, and referring thereto:—

Figure 1 is a side elevation of the invention as applied to the car, the device being shown in position for use in full lines, dotted lines 20 showing the position of the fender when swung back under the car. Fig. 2 is a front elevation of the device.

25 **Z** bars *a* under the car slidably hold a pair of **L**-shaped brackets *2*, the arms of each bracket being stiffened by braces *3*. Pivoted at 4 to each bracket *2* is a link *5*, and a shaft *6* connects the front ends of the links *5*. Pivoted on the shaft *6* and lying next to each link *5* is a lever *7*, the forward ends of the 30 levers carrying a buffer roller *8*. Pivoted also at both ends of the shaft *6* are links *9*; the rear end of each link is rounded, as shown in Fig. 1, and is adapted to articulate in a correspondingly curved notch *10* formed in the lower end of each of the associated brackets *2*. Each bracket *2* has two of these notches *10*, one notch being in the front edge and the other in the rear edge of the bracket. The end of each link *9* is provided with a stud *11* which is detachably engaged by a 35 detent *12*. Each detent *12* is a double detent having a forward hook *13* and a rear hook *14*. When the fender is in working position the links *9* are held in the front notches by the front hooks *13*. As the studs *11* are concentric with the curved ends of the links *9* they do not disturb or strain the detents *12* as the links *9* rock in the rounded seats when in use. A shaft *15* connects the rear curved 40 ends of levers *7*. Pivoted to each end of the shaft *15* just inside of the lever *7* is a short arm *16*, and the front ends of the arms *16* are connected by a horizontal shaft *17*. The shafts *15* and *17* are also connected at intermediate points by two short arms or links *18* 45 as shown in Fig. 2. A series of slats *19* have

their lower front ends articulated with the shaft *17*, the upper rear ends of slats *19* being articulated with a shaft *20* which is detachably supported by a pair of brackets *21* which 50 extend rigidly forward from the brackets *2*. In order to hold the slats *19* properly spaced apart a connecting bar *22* extends across underneath the series of slats and each slat is riveted thereto. Each arm *21* has a notch 55 at its upper edge which receives the adjacent end of the shaft *20*, and a hook *23* which is pivoted to the arm *21* engages the adjacent end of the shaft *20* and holds the shaft *20* detachably in place. A series of slats *24*, 60 which are spaced apart by a bar *25*, have their lower ends articulated to the shaft *20*, being staggered with the slats *19*, as shown in Fig. 2. The upper ends of slats *24* are curved as shown in Fig. 1 and attached to a 65 horizontal bar *26* which rests upon the sill *1* of the car. A series of slats *27* curved parallel with the levers *7* have their upper rear ends articulated with the shaft *15* and are 70 spaced apart by bars *28*, *29* and *30*. The bars *28*, *29* and *30* are attached at each end to the adjacent levers *7*. All the slats *19*, *24* and *28* may be formed of any suitable material such as a spring steel.

In use the slats occupy the position shown 85 in Fig. 1. As the car moves along the roller *8* may swing up and down slightly, the levers *7* rocking on shaft *6* permitting of this movement. When an object is encountered the scoop portion comprising roller *8* and slats *27* 90 shove under the object while the slats *19* and *24* act as buffers for softening the rearward movement of the object over the scoop, and prevent the object from sliding back over the rear end of the scoop and under the car. To 95 swing the structure under the car hooks *23* are lifted to disengage shaft *20*, and the shaft is then lifted out of the notches in arms *21*, the shaft *20* is then swung forward in a circle, of which shaft *17* is the center, and at the 100 same time bar *26* is lifted from the sill *1*. The slats *19* are laid down upon the slats *27*, the shaft *20* lying a short distance back of roller *8*, and the slats *24* are swung around shaft *20*, and bar *26* rested upon the ends of slats 105 *19* which are curled around shaft *17*. The structure when thus folded may be swung back under the car by disengaging hooks *13* from studs *11*. This allows the links *9* to be removed from their seats so that the parts 110 can swing in a circle, indicated by the dotted arrow, into the position shown in dotted

lines, the links 9 being then placed in engagement with the rear seats of the brackets 2 and caught by the hooks 14. This construction forms what might be called three leaves of slats. One leaf being formed by the slats 27, the intermediate leaf being formed by slats 19, and the upper leaf being formed by slats 24.

By unbolting the brackets 2 from the sill 10 of the car, the brackets 2 carrying the entire fender, may be slid forward out of the Z bars a to remove the fender from the car when desired.

What I claim is:—

1. A fender comprising brackets attached to the car, links pivoted to the brackets, a front leaf hinged to said links, and arms connected with said leaf with their rear ends adapted to detachably engage said brackets when the leaf is projected in front of the brackets or swung back behind said brackets.

2. A fender comprising supporting brackets attached to the car, links pivoted to said brackets, a leaf hinged at an intermediate point to said links, arms connected with the leaf, and means for detachably connecting the rear ends of said arms with said brackets.

3. A fender comprising supporting brackets, each bracket having a pair of opposite notches near its lower end, a link pivoted to each bracket, a shaft connecting the front end of said links, a leaf pivoted on said shaft, an arm connected to each end of said shaft, the rear end of each arm being rounded and adapted to fit either of the notches in the associated bracket, and means for detachably holding the rounded ends of the arms in position.

4. A fender comprising supporting brackets, links pivoted to said brackets, a leaf pivoted to the front ends of said links, arms connected with the leaf, the rear ends of each of said arms having a stud and being curved concentric with the stud, the associated bracket having a rounded notch forming a seat for the end of the arm, and a hook pivoted to the bracket for engaging said stud.

5. A fender comprising supporting brackets, links pivoted to the supporting brackets, a leaf having a curved rear portion and pivoted to said links, arms extending rearwardly from the pivotal connection between said links and leaf, and means for detachably engaging the rear ends of said arms with said supporting brackets.

6. A fender comprising supporting brackets, links pivoted to the supporting brackets, a leaf having a curved rear portion and pivoted to said links, arms extending rearwardly from the pivotal connection between said links and leaf, means for detachably engaging the rear ends of said arms with said supporting brackets, short arms pivoted to the rear ends of said leaf, a shaft connecting the short arms, an intermediate leaf having its

front edge journaled on said shaft, and means for supporting the rear edge of the intermediate leaf.

7. A fender comprising supporting brackets, links pivoted to the supporting brackets, a leaf having a curved rear portion and pivoted to said links, arms extending rearwardly from the pivotal connection between said links and leaf, means for detachably engaging the rear ends of said arms with said supporting brackets, short arms pivoted to the end of said leaf, a shaft connecting the short arms, an intermediate leaf having its front edge journaled on said shaft, means for supporting the rear edge of the intermediate leaf, said last means comprising rigid arms on the supporting brackets, the rigid arms having notches, a shaft extending along the rear edge of the intermediate leaf and engaging in said notches, and hooks pivoted to the rigid arms for engaging said shaft and holding it in said notches.

8. A fender comprising supporting brackets, links pivoted to the supporting brackets, a leaf having a curved rear portion and pivoted to said links, arms extending rearwardly from the pivotal connection between said links and leaf, means for detachably engaging the rear ends of said arms with said supporting brackets, short arms pivoted to the rear ends of said leaf, a shaft connecting the short arms, an intermediate leaf having its front edge journaled on said shaft, means for supporting the rear edge of the intermediate leaf, said last means comprising rigid arms on the supporting brackets, the rigid arms having notches, a shaft extending along the rear edge of the intermediate leaf and engaging in said notches, and hooks pivoted to the rigid arms for engaging said shaft and holding it in said notches, a rear leaf with its front edge connected with the latter shaft, the upper portion of the rear leaf being curved and adapted to rest on the car sill.

9. A fender comprising supporting brackets, links pivoted thereto, a forward leaf pivoted to the ends of said links, short arms pivoted to the rear of said leaf, a shaft connecting the free ends of said arms, an intermediate leaf with its front edge attached to said shaft, a second shaft to which the rear edge of the intermediate leaf is attached, a third leaf with its front edge articulated with the second shaft, the intermediate leaf being foldable forward over and against the forward leaf, the rear leaf being foldable backward onto the intermediate leaf and allowing the structure to be swung on said links under the car, and arms connected with said links and detachably engaging the supporting brackets at the front or rear for holding the structure extended forward of the brackets or behind said brackets when the structure is folded.

10. A fender comprising a scoop, means

for holding the scoop extended in front of the car, means for allowing the scoop to be swung back under the car, and means for detachably holding the scoop when retracted under the car, brackets slidably mounted in **Z** bars under the car and supporting the first means.

5 In testimony whereof, I have hereunto set

my hand at Los Angeles, Cal. this 23d day of April, 1907.

FOREST HALM.
